UNITED STATES PATENT OFFICE.

FRED A. ROGERS, OF ATWOOD, KANSAS.

ENGINE-STARTER.

No. 914,308.

Specification of Letters Patent. Patented March 2, 1909.

Application filed July 8, 1908. Serial No. 442,545.

To all whom it may concern:

Be it known that I, FRED A. ROGERS, a citizen of the United States, residing at Atwood, in the county of Rawlins and State of Kansas, have invented new and useful Improvements in Engine-Starters, of which the following is a specification.

This invention relates to engine starters, the invention being especially designed with reference to automobiles for the purpose of enabling the driver to start the engine while seated on the machine and without the necessity of manipulating the other hand crank at the front of the machine.

With the above and other objects in view, the nature of which will more fully appear as the description proceeds, the invention consists in the novel construction, combination and arrangement of parts as hereinbelow after fully described, illustrated and claimed.

In the accompanying drawing.—Figure 1 is a side elevation of an automobile showing the invention applied thereto. Fig. 2 is a plan view of the chassis omitting the hood and showing the starter applied to the crank shaft of the engine. Fig. 3 is an enlarged detail plan view of the crank arm and sleeve, showing also a portion of the crank shaft. Fig. 4 is a longitudinal section through the same, showing the ratchet sleeve and crank shaft in elevation. Fig. 5 is a vertical cross section through the same.

The starting device is best illustrated in detail in Figs. 3, 4 and 5 wherein it is seen to comprise a ratchet sleeve 1 which is keyed fast on the crank shaft or engine shaft indicated at 2. This sleeve is generally cylindrical and provided with longitudinal ribs or teeth 3 preferably ratchet-shaped and best illustrated in Fig. 5. At opposite ends of the ratchet sleeve 1, which may be of any suitable length, there are arranged bearing collars 4 which are also keyed to the shaft 2 as shown at 5. These bearing collars are rabbed along their inner peripheral edges as shown at 6 adapting them to receive a flush seated crank sleeve 7 which thus has a bearing at its opposite ends on the rabbed seats of the bearing collars 4 as clearly shown in Fig. 4.

The crank sleeve 7 is provided in one side with a rectangular opening 8 and mounted adjacent to one side of said opening is a series of dogs 9, the same being fulcrumed on a common fulcrum pin or rod 10 extending along one side of the aperture 8. The dogs

are also provided with extensions 11 adapted to come in contact simultaneously with a tripping bar 12 preferably arranged over the sleeve 7 as shown in Fig. 5 whereby all of the dogs are tripped at a certain point in the throw of the crank arm 13 with which the sleeve is provided. The dogs 9 are all held normally in engagement with the teeth of the ratchet sleeve 1 by means of springs 14.

Extending along one side of the chassis is a two-armed operating lever one arm 15 of which has a jointed connection at 16 with the extremity of the crank arm 13 as shown in Fig. 2. The other arm 17 of said lever is provided with a hand piece or treadle 18 located within convenient access to the driver or motorman while the two arms 15 and 17 of said lever are connected by a transverse longitudinal portion 19 which is mounted in a suitable bearing 20 secured to the frame of the chassis as shown in Figs. 1 and 2.

In order to start the car, the motorman or driver while seated in their usual place on the machine, rocks the arm 13 of the crank sleeve upward, the weight of the parts serving to return them to their normal position in which the crank arm 13 extends laterally away from the crank shaft 2 and lies in a substantially horizontal plane under the hood of the engine. After the operator repeats the operation above described a sufficient number of times, the necessary compression of the explosive mixture is obtained in the cylinder of the engine and the motorman by then operating the sparking lever or other suitable part of the ignition apparatus to cause a spark in one of the cylinders will effect the starting of the engine all of which is accomplished without the driver leaving his seat.

It will, of course, be understood that the operating lever may be either hand or foot operated as may be found most expedient and the starting of the device may be applied to the engine shaft irrespective of the type of engine, that is to say, whether the engine shaft extends longitudinally or transversely

105

I claim:

1. A starting device of the class described comprising in connection with an engine shaft for motor-driven vehicles, a ratchet sleeve fast on the engine shaft, bearing collars fast on said shaft at opposite ends of said sleeve, a crank sleeve embracing the ratchet

110

sleeve and journaled on said collars, a crank arm extending radially off from said crank sleeve, one or more spring pressed dogs carried by the crank sleeve and engaging the ratchet sleeve, and an operating lever having an arm thereof connected with the crank arm of said crank sleeve, said operating lever being arranged within reach of the driver on his seat on the machine.

10 2. The combination with the engine shaft of a motor-driven vehicle, of a ratchet sleeve fast on said shaft, bearing collars arranged at opposite ends of said sleeve and also fast on the engine shaft, a crank sleeve journaled at 15 its opposite ends on said collars and inclosing the ratchet sleeve, a plurality of dogs ful-

crumed on said crank sleeve and engaging the ratchet sleeve, a crank arm extending laterally away from said crank sleeve, an operating lever having a jointed connection 20 with said crank arm and arranged within reach of the driver in his seat on the machine, and means for simultaneously tripping all the dogs at a certain point in the throw of the crank arms, substantially as described. 25

In testimony whereof I affix my signature in presence of two witnesses.

FRED A. ROGERS.

Witnesses:

S. F. SNYDER,
H. B. ROGERS.
